ELECTRIC STARTING MOTOR

Jakob Bohli, Solothurn, Switzerland

Application July 7, 1933, Serial No. 679,386
In Germany July 14, 1932

2 Claims. (Cl. 290—38)

This invention relates to a certain system of electric starting motors, the rotor shaft of which is coupled by means of an overrunning clutch to the pinion shaft which engages a ring of teeth mounted on the engine flywheel. For the starting operation a special field coil is first switched in series to the rotor causing a rotation of the rotor opposite to the working direction, the pinion is brought electromagnetically into engagement with the ring of teeth on the flywheel, and after the pinion has been moved into full engagement, the main field coil is switched in and the current in the special field coil is changed so that the effect of the latter is added to the one of the main field coil. Starting motors of the usual design without special field coil have the disadvantage that if the teeth of the pinion strike against the teeth of the flywheel when moving into engagement, the pinion is rotated with respect to the flywheel teeth under the full momentum of the armature mass the result being rapid wear of the teeth of the flywheel and of the pinion.

It has now been proposed in the Patent No. 1,910,588 to use a special field coil together with an overrunning clutch; this special field coil causes a rotation of the rotor opposite to the working direction of rotation when moving the pinion into engagement thereby preventing the momentum of the armature from having a damaging effect if the teeth of the pinion strike against the teeth of the flywheel as the pinion shaft is turned only by the friction of the rotating overrunning clutch.

According to the invention the connection for this system is made in such a way that in the first switch step of a known blade-type switch the special field coil is switched in a sense opposite to the working direction of rotation, whilst in the second switch step the pinion is displaced electro-magnetically into the ring of teeth and by this movement after complete engagement another switch is closed operating a relay by means of which the main switch is closed and at the same time the switch for the special field coil is operated in such a way that the direction of the current in the latter is reversed whereby the effect of same is added to the one of the main field coil.

On the drawing an example of the invention is shown in a wiring diagram.

a is the engine ring of teeth on the flywheel, *b* is the starting motor, *c* the pinion shaft and *d* the pinion, *e* the main field coil and *f* the special field coil. The pinion shaft *c* is displaced axially by the electro-magnetic coil *g*. After the pinion

has fully engaged the ring of teeth the switch *h* is in the closed position. This switch operates a relay *i* provided for the main coil switch *l* and the field coil switch *n*. This relay consists of the electro-magnetic coil *k*, and the main switch proper *l* for the starter which is fixed to the switch shaft *m* on which the commutator *n* for the special field coil *f* is arranged also. *o* represents a known blade-type switch with three positions. The battery *v* supplies current to the starter and the starter relay. In the nought position of the switch *o* all the circuits are switched out. In the first switching position the special field coil *f* is switched in series to the rotor so that the latter is turned in the opposite sense with respect to the working direction of rotation. In the second switching position of the switch *o* current is also supplied to the coil *g*. Now the pinion shaft is displaced and the pinion brought into engagement. After the latter has fully engaged the switch *h* is closed also. The result of this is that under the influence of the electro-magnetic coil *k* the main switch is closed and at the same time the special field coil switched over i. e. parallel to the rotor. The rotor rotates now in the working direction of rotation and the starter works as a compound motor. After the internal combustion engine has started on its own power the blade-type switch is released. It returns to the first switching position i. e. the coil *g* is switched out again and the pinion disengages the ring of teeth, the switch *h* is opened also by this displacement of the pinion shaft. In consequence of this the main current switch is again opened and the special field coil switched over whereby the rotor is retarded and quickly brought to a stand-still. In the nought position of the switch *o* the relay for the special field coil is now again switched out.

By means of the blade-type switch a relay for heating up the incandescent plugs which are used for Diesel engines, may be operated in such a way that in the first and second switching position current is supplied to a relay which closes the circuit for said incandescent plugs. This relay consists of the electro-magnetic coil *r* and the switch proper *q*. *s* represents the incandescent plugs, *t* the control lamp and *u* the battery used for these incandescent plugs.

What I claim is:

1. In an electric starting motor system for internal combustion engines, in combination a rotor, a field coil, a special field coil, a pinion, a pinion shaft, an overrunning clutch, said pinion coupled to the pinion shaft by means of said overrunning clutch, an engine flywheel, a ring of teeth mounted

on the latter, an electro magnet for operating said pinion shaft, a switch operated by said pinion shaft in such a way that after full engagement of the pinion in the ring of teeth on the flywheel 5 said switch is closed, a main current switch, a switch for the special field coil fixed to the latter, an electro magnet for operating the two latter switches, a battery for the starter, a three-position 10 blade-type switch adapted to switch out all circuits in the nought position and to switch in the first switching position the special field coil into the circuit so that the rotor rotates opposite to the working direction of rotation and adapted to operate in the second switching position said first 15 mentioned electro magnet which displaces the pinion into engagement and closes said first mentioned switch which renders operative the main and the special field coil switches in such a way that the main circuit is closed and the current in 20 the special field coil is changed so that the effect of the latter field is added to the one of the main field coil.

2. In an electric starting motor system for internal combustion engines, in combination a rotor, 25 a field coil, a special field coil, a pinion, a pinion shaft, an overrunning clutch, said pinion coupled to the pinion shaft by means of said overrunning clutch, an engine flywheel, a ring of teeth mounted

on the latter, an electro magnet for operating said pinion shaft, a switch operated by said pinion shaft in such a way that after full engagement of the pinion in the ring of teeth on the flywheel 5 said switch is closed, a main current switch, a switch for the special field coil fixed to the latter, an electro magnet for operating the two latter switches, a battery for the starter, a three-position 10 blade-type switch adapted to switch out all circuits in the nought position, to switch in the first switching position the special field coil into the circuit so that the rotor rotates opposite to the working direction of rotation and adapted to operate in the second switching position said first 15 mentioned electro magnet which displaces the pinion into engagement and closes said last mentioned switch which renders operative the main and the special field coil switches in such a way that the main circuit is closed and the current in the special field coil is changed so that the effect 20 of the latter field is added to the one of the main field coil, a relay, incandescent plugs, a battery, said relay adapted to work in the first and second switching positions of said blade-type switch and to operate the heating-up of the incandescent 25 plugs by switching in said battery.

JAKOB BOHLI.
